[57] **CLAIM**

The ornamental design for a water sprinkler base, as shown and described.

DESCRIPTION

FIG. 1 is a perspective view taken from the top, front, and left side of a water sprinkler base showing our new design;

FIG. 2 is a right side elevational view thereof;

FIG. 3 is a front elevational view thereof;

FIG. 4 is a rear elevational view thereof;

FIG. 5 is a top plan view thereof; and

FIG. 6 is a bottom plan view thereof.

The broken line representation of a sprinkler head in FIG. 1 is for purposes of illustration only.
